UNITED STATES PATENT OFFICE.

THOMAS H. WHITE, OF SOUTH CHICAGO, ILLINOIS.

JOURNAL-BOX.

1,310,642.

Specification of Letters Patent. Patented July 22, 1919.

Application filed February 28, 1918. Serial No. 219,632.

To all whom it may concern:

Be it known that I, THOMAS H. WHITE, a citizen of the United States, residing at South Chicago, in the county of Cook and State of Illinois, have invented certain new and useful Improvements in Journal-Boxes, of which the following is a specification.

This invention has relation to journal boxes for railway rolling stock and has for 10 an object to provide primarily a journal box adapted to be closed and locked in a manner to prevent removal of lubricant or waste, also brass bearings.

Another object of the invention is to provide a journal box formed with an opening through which waste and lubricant may be introduced, and closed by a screw threaded plug comprising a locking means operable by a key to retain the plug against rotation and consequent removal when once inserted without the use of the key for which the lock is designed.

In addition to the foregoing my invention comprehends improvements in the details 25 of construction and arrangement of the correlative parts to be hereinafter more fully described and particularly set forth in the appended claims:

In the accompanying drawings in which 30 similar and corresponding parts are designated by the same characters of reference throughout the several views in which they appear:—

Figure 1, is a view in longitudinal section taken through a journal box embodying my improvement.

Fig. 2, is a view thereof in end elevation.

Fig. 3, is a detail view in perspective illustrating a receptacle for holding the weight, 40 and

Fig. 4, is a detail view on an enlarged scale illustrating the locking mechanism.

With reference to the drawings, 10 indicates the casing of the journal box, and 11 45 indicates the journal. The brasses 12 are superposed upon the upper surface of the journal in the usual manner. Mounted upon the upper surface of the brasses is an angular plate including an attaching portion 13, an upwardly extending portion 14, and a horizontal portion 15 extending toward the outer end of the journal box and through an opening 16 in the upper plate thereof. The opening 16 and the angular 55 plate is covered by a movable hood 17 having its front end open whereby the interior

may be viewed. Extending centrally from the end of the journal is a pin 18 to which the lower end of a vertically extending gage rod 19 is pivotally secured. The upper end 60 of the gage rod 19 extends through an opening in the horizontal portion 15 of the angular plate and is provided upon its front surface with a series of vertically spaced 65 graduations.

The front end of the journal box is left open and provided with a plurality of inwardly extending lugs 20 which are apertured to receive bolts. A relatively thick plate 21 is applied to said open end of the 70 journal box and is formed in its body with holes and in its outer surface with countersunk rectangular openings 22 registering therewith and of a size to permit the introduction therein of bolts 23 and to snugly 75 engage the ends of the bolts to prevent rotation thereof. The threaded portion of the bolts extend through the lugs 20 and nuts 24 are applied to the inner ends of the bolts to bind the plate 21 in place. The bolts 24 80 may be applied by inserting the hand through a circular internally threaded opening 25 formed in the covering plate 21. It will be obvious that after the bolts 24 are once secured in place they cannot be removed from the outside of the journal box 85 because of the tightly fitting opening 22 which precludes the application of a wrench or other tool to the bolt. The internally threaded opening 25 is closed by a plug 26 90 having a rectangular extension 27 thereon to permit the application of a wrench thereto. The plug 26 is formed with a recess 28 adjacent the periphery to contain locking mechanism, and a radial opening 29 intersects the recess 28 to guide a radially movable locking bolt 30 which may extend beyond the periphery of the plug. The inner end of the locking bolt 30 is provided with a rightangular extension 31 engageable by the 100 ward 32 of the key which may be inserted through the keyhole 33. The bolt 30 is formed with a pair of spaced notches 34 in either of which one end of a leaf spring detent 35 may engage to releasably retain the 105 bolt in either a locked or unlocked position.

Disposed beneath the journal 11 within the journal box, is an elongated receptacle 36, shown in detail, in Fig. 3, and which is supported through the medium of a pair 110 of supporting legs consisting of springs 37 secured at a point intermediate their ends

to the under side of the receptacle whereby opposite ends may extend downward in diverging relation to resiliently support the receptacle and to urge the same against the under side of the journal. The receptacle 36 is filled with waste, and the waste is caused to bear against the under side of the journal to lubricate the same. I employ a novel form of lubricating device which consists of a vertical pipe 38 mounted in the rear end of the journal box and having its lower end extended at right angles as at 39 and disposed adjacent the bottom of the journal box. The pipe 38 is formed with a horizontal branch or extension 40 at a point adjacent the journal 11. The pipe 38 extends into the branch 40 through the medium of a lip 41 which extends well into said branch 40 and the branch 40 is furthermore in communication with the horizontal portion 39 as will be readily seen from Fig. 1. The branch 40 is provided with a plurality of jets 42 which are directed toward the journal, and the upper end of the pipe 38 is connected to a valve casing 43 having a valve 44 located therein and held in normally closed position by means of a comparatively heavy spring 45. The valve casing 43 is placed in communication with the brake pipe of the air brake system by means of a hose connection 46 and the valve 44 is designed to open to permit the entrance of air from the system into the branch 40 when the pressure exceeds the strength of the spring 45 to retain the valve 44 closed. The pipe 38 is of a comparatively small diameter so that very little of the air of the system may be required to supply the lubricant.

In practice, during the time that the train is in motion, the brake pipe will obviously be supplied with air at standard brake pipe pressure. It is necessary therefore, when the train is running to insure proper lubrication of the journal. To this end the spring 45 is adjusted so as to open when the brake pipe pressure reaches its predetermined running point whereby air is forced through the pipe 38 and deflected by the lip 41 into the branch 40 thereby producing an injector effect whereby oil or lubricant is elevated from the portion 39 which is submerged in oil into the branch 40 and directed by the force of air through the jets 42 upon the journal. Excess oil is wiped off the journal by the waste contained in the receptacle 36 and said receptacle may be formed with an opening in its bottom to permit the oil to drain back into the reservoir. It will be noted that when the train is not running the main brake pipe pressure will be, but this is as it should be inasmuch as the necessity for lubrication while the train is not in motion is not as imperative. It will be noted that after the waste is introduced into the journal box and the plug

26 inserted it can be rotated until the plug 30 is brought to a point to enter a recess 47 in the wall of the threaded opening 26 whereby when the key is rotated to the left the locking bar may be moved thereinto and the threaded plug thus held against rotation. The theft of waste and lubricant is thus effectively prevented and the loss to railroads from this source, which is considerable, thereby precluded. The condition 75 of the brasses may be observed without opening the journal box, inasmuch as the proximity of any one of the graduations on the vertical gage bar 19 to the lower edge of the portion 15 of the angular plate will indicate the brasses.

Thus it will be seen that I have provided a journal box embodying many novel features of construction, which is simple in construction and whose slight increase in cost of 85 manufacture will be amply compensated by a saving in the loss of lubricant and waste. It will furthermore be seen that the damage to journals and rolling stock would be prevented owing to the method of lubrication which 90 insures lubrication of the journals at a time when the lubrication is most required. Other uses and advantages will be readily apparent to those skilled in the art to which this invention appertains.

While I have illustrated and described my invention with some degree of particularity I realize that in practice various alterations thereover may be made, and I therefore desire to reserve the right and privilege of 100 changing the form of the details of construction and arrangement of the correlative parts without departing from the spirit of the invention or the scope of the appended claims.

Having thus described my invention what I claim as new and desire to secure by Letters Patent is:—

1. In a journal box having a threaded opening to permit the introduction of lubricant, a threaded plug inserted in said opening, and means in the plug operable subsequent to its insertion to prevent rotation of the plug.

2. In a journal box having one side open, a plurality of inwardly extending apertured lugs formed around said opening, a plate adapted to be applied to said opening having holes and countersunk rectangular openings, bolts inserted in said holes and having rectangular heads to engage the countersunk openings, nuts applied to the inner ends of the bolts to secure the plates to the lugs, said plate having a threaded opening, a plug inserted in said opening, and means operable subsequent to its insertion to prevent rotation of the plug.

3. In a journal box having internally threaded openings to permit the introduction of lubricant, a plug adapted to be in-

serted therein having a recess, a locking bar movable in said recess and having a right-
angular extension, said plug having a key
hole to permit the insertion of the key to
5 engage said rightangular extension to move
the locking bar, and a detent engaging the
locking bar to retain the same in locked or
unlocked position.

4. In a journal box, the combination with
10 a plate closing the outer end of said box
and having an internally threaded opening;
of an externally threaded plug adapted to
be screwed into said opening and its body
having a recess with a radial opening lead-
15 ing therefrom outward, an angular exten-
sion on the outer end of said plug, a radially
movable locking bolt within said opening
and its inner end standing within said re-
cess, and means for actuating the bolt from
20 its inner end.

5. In a journal box, the combination with
a plate closing the outer end of said box
and having an internally threaded opening;
of an externally threaded plug adapted to
25 be screwed into said opening and its body
having a recess with a radial opening lead-
ing therefrom outward, an angular exten-
sion on the outer end of said plug, a radially
movable locking bolt mounted in said open-
30 ing and having a right-angular extension at
its inner end standing within said recess, a
spring detent for retaining said bolt in
either of two positions, and manually oper-
able mechanism engaging said extension for
35 actuating the bolt.

6. In a journal box, the combination with
a plate having an internally threaded cir-
cular opening, and means for securing the
plate across the outer end of the box; of an
40 externally threaded plug adapted to be
screwed into said opening, the plug having
a recess in its body and a radial opening
leading therefrom and also having a key-
hole through its front wall communicating

with said recess, a bolt movably mounted in 45
said radial opening and having an extension
at its inner end mounted in said recess ad-
jacent the key-hole and adapted to be actu-
ated by a key inserted therein, and a spring
detent for holding the bolt in either of two 50
positions.

7. In a journal box, the combination with
a body having its front end open and sur-
rounded by inwardly projecting lugs; of a
55 plate adapted to close said front end, said
plate having holes continued in counter-sunk
openings and registering with said lugs, and
the plate also having a large central open-
ing, bolts whose shanks are mounted in said
60 holes and project through the lugs to re-
ceive nuts at their inner ends and whose
heads are counter-sunk in said openings, a
plug removably fitting the large central
opening, and means for locking the plug in
65 place.

8. In a journal box, the combination with
a body having its front end open and sur-
rounded by inwardly projecting lugs; of a
70 plate adapted to close said front end, said
plate having holes continued in counter-sunk
openings and registering with said lugs, and
the plate also having a large central open-
ing, bolts whose shanks are mounted in said
75 holes and project through the lugs to re-
ceive nuts at their inner ends and whose
heads are counter-sunk in said openings, a
plug screwed into said large central opening
and closing access to said nuts, locking
means carried within the plug for engaging
the plate, and means for actuating said lock
80 from the exterior of the plug.

In testimony whereof I affix my signature
in presence of two witnesses.
